UNITED STATES PATENT OFFICE.

HAROLD S. BRAUTIGAM, OF BRACKENRIDGE, PENNSYLVANIA, ASSIGNOR TO ALLEGHENY STEEL COMPANY, A CORPORATION OF PENNSYLVANIA.

JOURNAL-BOX LID.

Application filed May 4, 1926. Serial No. 106,606. Renewed September 17, 1926.

This invention relates to journal boxes for railway car trucks and more particularly to lids for such boxes and springs for closing the same.

5 The standard A. R. A. (American Railway Assn.) journal box for railway car trucks is provided with a lid or cover hinged along its top edge to the box and with a spring by means of which the lid is held in either open or closed position. Various types 10 of springs or spring devices have been suggested for use in this connection, but with those most commonly used, the lid, when in closed position, bears tightly only on the lower box face and stands away varying distances from the side and top box faces. This 15 is necessarily so on account of the construction and operation of this spring.

Within the last few years, journal box lid 20 closing spring means have appeared and at least one of these provides a self adjusting structure by means of which the lid is caused to bear evenly and tightly on the top, sides and bottom faces which define the journal 25 box opening and this, irrespective of the fit of the lid scrolls on the hinge pin or the fit of the hinge pin within its hole in the box lug.

The lid and lid closing means to which 30 reference has been made is disclosed in an application for patent filed by Leigh W. Hostettler and employs a torsion spring and a spring tensioning member which is mounted on the hinge pin and bears on the spring 35 on the opposite side thereof from the lid proper.

An object of this invention is to produce a device broadly functioning in the same manner as the device of said Hostettler application, but which is simpler and cheaper for the reason that it avoids the use of a spring tensioning member.

This, as well as other objects which will 40 readily appear to those skilled in this particular art, I attain by means of the structure described in the specification and illus-

trated in the drawings accompanying and forming part of this application.

In the drawings, Figure 1 is an end elevation of a journal box showing this invention in connection therewith and Fig. 2 is a longitudinal sectional view partly broken away and taken on the line 2-2 of Fig. 1.

In the drawings, the journal box proper is provided with a flat faced top wall 3, a flat 55 faced bottom wall 4 and side walls 5 which also have flat faces and which lie in the plane of the top and bottom walls.

The mouth formed by these walls is rectangular and is inclined as shown, as is now 60 common.

The upper portion of the box proper is projected in the form of a box lug 6 formed with a central spring bearing cammed portion 7 and rounded side portions 8. The 65 cammed portion has two cam faces 7^a and 7^b. The lug is provided with a pin hole 9 which extends through the same from end to end.

A hinge pin 10 lies within the pin hole 70 and projects outwardly therefrom beyond each end of the lug 6 to receive the lid scrolls.

The journal box lid is of rectangular outline and is preferably stamped from sheet metal such as steel. The lid chosen for illustration is provided with a depending marginal flange 11 and a finger piece 12 which projects from its lower edge. The lid is stiffened by being embossed as shown.

The lid scrolls 13 project upwardly from 80 the lid body proper and embrace the hinge pin 10 on opposite sides of the box lug and are so formed as to provide spaces on opposite sides of the box lug or between the ends of the box lug and the lid scrolls.

The scrolls are so formed as to provide substantial clearance between their inner curved surfaces and the hinge pin which they embrace. The clearance is preferably greatest at right angles or perpendicular to 90 the plane of the lid proper or box face when the lid is in closed position.

The lid is held in closed position by means of the spring which is so formed and so mounted that its closing pressure is applied to the center of the lid whereby the lid is caused to bear evenly over the entire box face which includes the top, bottom and sides.

The spring is preferably formed from round steel wire and carries an anti-friction roller 15 which bears on one or the other of 10 the cam faces of the box lug depending upon whether the lid is in open or in closed position.

The roller 15 is placed in position at the center of the length of wire from which the 15 spring is made and before the same is bent to form.

The spring is double and bilaterally symmetrical. The roller 15 is carried by the portion 16 which connects the two halves.

20 The free ends 17 are bent inwardly so as to project one toward the other and are anchored to the lid by retaining plate 18 which is riveted in place. At an intermediate portion 19 each half is coiled about the hinge 25 pin 10 and the portions 20 between these coils and the free ends 17, are curved away from the lid on the arc of a circle. Portions 21 leave the coils 19 on the under side of the hinge pin and extend upward above 30 the hinge pin and then bend upon themselves and extend downwardly and join one another in connecting portion 22 which carries anti-friction roller 15.

From the preceding description, taken in 35 connection with the drawings, it will be apparent that the spring device exerts its pressure at the center of the lid and will cause the lid to bear evenly over the entire box face, since there is nothing tending to 40 lift the top of the lid away from the box face. The function of retaining plate 18 is to tie the lid and spring together when the lid is in open position and when moving from open to closed position.

45 From the construction shown, it will be apparent that variations due to inaccuracies in manufacture or those arising from wear of the parts are compensated for, since the device is self fitting.

Having thus described this invention, what is claimed is:

1. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means 55 comprising a spring element having a portion thereof anchored to the lid, two portions which encircle the hinge pin on opposite sides of said lug and a portion which extends above and beyond the hinge pin is 60

bent upon itself and cooperates with said lug.

2. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a spring element comprising one portion thereof anchored to the lid, two portions are coiled above the hinge pin on opposite sides of said lug and another portion which extends from said coiled portions above and beyond the hinge pin is bent 70 upon itself and cooperates with said lug. 75

3. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a spring element having its ends anchored to the lid, intermediate portions which encircle the hinge pin on opposite sides of said lug and a portion which extends above and beyond the hinge pin, is bent 80 upon itself and carries an anti-friction member which bears on said lug. 85

4. In a journal box, the combination with the box proper provided with a spring bearing lug and having a lid pivotally connected thereto, of means for applying a substantially equally distributed yielding pressure 100 against the outer face of the lid near the center thereof, said means comprising a double bilaterally symmetrical spring with the free end of each half anchored to the lid, intermediate portions which encircle the hinge pin on opposite sides of said lug and a central portion which extends above and beyond the hinge pin and carries an anti-friction member which bears on said lug. 105

5. In a journal box, the combination with the box proper provided with a spring bearing lug and having a lid pivotally connected thereto, of means for applying a substantially equally distributed yielding pressure 110 against the outer face of the lid near the center thereof, said means comprising a double bilaterally symmetrical spring with the free end of each half anchored to the lid, intermediate portions which encircle 115 the hinge pin on opposite sides of said lug and a central portion which extends above and beyond the hinge pin and cooperates with said lug. 120

6. In a journal box, the combination with the box proper provided with a spring bearing lug and having a lid pivotally connected thereto by means of a hinge pin which ex- 125

tends through the lug, of means for applying a substantially equally distributed yielding pressure against the outer face of the lid near the center thereof; said means comprising a double bilaterally symmetrical spring with the free end of each half anchored to the lid, spaced intermediate portions each of which is coiled about the hinge

pin and a central portion which extends above and beyond the hinge pin, is bent 10 downwardly upon itself and cooperates with said lug.

In testimony whereof, I have hereunto subscribed my name this 19th day of April, 1926.

HAROLD S. BRAUTIGAM.
